INVENTOR

UNITED STATES PATENT OFFICE.

ALFRED C. BLATZEK, OF MILWAUKEE, WISCONSIN.

DESIGN FOR A COMMERCIAL CONTAINER OF TOILET PREPARATIONS.

52,068.

Specification for Design.

Patented June 4, 1918.

Application filed January 15, 1918. Serial No. 211,995. Term of patent 7 years.

To all whom it may concern:

Be it known that I, ALFRED C. BLATZEK, a citizen of the United States, residing at the city of Milwaukee, in the county of Milwaukee and State of Wisconsin, have invented a new, original, and ornamental Design for a Commercial Container of Toilet Preparations, of which design the following is a specification, reference being had to the accompanying drawing, forming part thereof.

The figures numbered 1, 2 and 3 are front view, side-view and plan respectively of a container showing my new design.

I claim:

The ornamental design for a commercial container of toilet preparations as shown.

ALFRED C. BLATZEK.

Witnesses:

MYRTLE WILLE,
FERN KAUFMANN.
